CLAIM

The ornamental design for a beacon light, as shown and described.

DESCRIPTION

FIG. 1 is an isometric front view of a beacon light showing the new design;

FIG. 2 is a front view of the design of FIG. 1;

FIG. 3 is a back view of the design of FIG. 1;

FIG. 4 is a right side view of the design of FIG. 1;

FIG. 5 is a left side view of the design of FIG. 1;

FIG. 6 is a top view of the design of FIG. 1; and,

FIG. 7 is a bottom view of the design of FIG. 1.

The broken lines show portions of the article which form no part of the claimed design.

1 Claim, 7 Drawing Sheets(56)
